United States Patent Office

Des. 217,422
Patented May 5, 1970

217,422

SHIRT

Norman L. Traeger, Columbus, Ohio, assignor to Varsity House, Inc., Columbus, Ohio, a corporation of Delaware

Filed May 7, 1969, Ser. No. 17,048

Term of patent 14 years

Int. Cl. D2—01

U.S. Cl. D2—46

The figure presents a front elevational view of a shirt, showing my new design, the back being plain and conventional.

I claim:

The ornamental design for a shirt, substantially as shown and described.
